carrier 9 which in dependence on the pump pressure produced acts on said carrier in the sense of a stroke execution. The action of the plunger 14 in response to the pressure in cylinder 13 is resisted by a spring 16 of a definite value acting upon the cylinder block carrier 9 at the point 17 and at a fixed point 18.

The pump operates as follows: The pressure set up in the conduit 12 by a certain pressure medium consumption by the piston 14 sliding in the cylinder 13 produces a force which tends to deflect the cylinder block carrier into its zero position, as of course this piston is supported against a fixed point. This force is counteracted by an external force produced by the spring 16 tending to deflect the cylinder block carrier 9 towards its maximum stroke position. The two forces balance one another so that a pressure may occur in the conduit 12 in dependence on the spring tension. The special piston 14 of Fig. 1 may be dispensed with if—as shown in Fig. 2—the cylinder block carrier 9 is not arranged concentrically about an axis 10 but is swingable about an eccentric axis 19. In the latter case the pressure produced in the pump cylinder acts on the cylinder block carrier 9 in the sense of a stroke reduction. This embodiment further differs from that of Fig. 1 in that the control surface is not plane but—as previously proposed elsewhere—has the form of a sphere 20, in which case the support axially guiding the cylinder block is dispensed with. Naturally, however, it is equally possible to provide for a plane control surface. In any case it is, nevertheless, necessary that the cylinder block carrier 9 be articulately connected with the driving flange 2 by means of a special centering member 21 in a ball on said driving flange. In this way the support of the cylinder block is free from static determination. This kind of support allows compensation for displacements due to conditions in the course of movement.

In the case now under consideration, in which the cylinder block carrier 9 is swingable around an eccentric axis 19, this type of support is particularly important in so far as the position of the point of intersection of the cylinder block axis and the driving flange axis is always precisely determined by the concentric guiding member 21, and the slight motions caused by the eccentric position of the cylinder block carrier 9 relative to the cylinder block 7 due to the stroke adjustment are received by the control surface without disturbing effects.

The centering member 21 is acted upon by the tension of a spring 22 ensuring constant contacting of the cylinder block 7 with the control surface 20. In this connection it is advantageous to have the spring 22 simultaneously act on a check valve 24 connected with the high pressure side of a pump by means of a duct 25 and thus exert a dampening effect on the reversing motion of the cylinder block 7.

As shown in Fig. 2a, the eccentric pivot point 19 of the cylinder block carrier 9 lies in the normal N to the bisectrix W of the largest angle that is possible between the axis of rotation U and the cylinder block carrier axis V, because this normal N is the geometrical point for all circle centers touching the axis of rotation U and the cylinder block carrier axis V and because in this position the smallest possible deviation of the axial intersection point from the desired intersection point is afforded with the result that the

above described sliding motion of the cylinder block 9 on the control surface 20 at stroke adjustments is reduced to the smallest possible amounts.

5 The embodiment according to Fig. 3 is similar to that shown in Fig. 2, possesses an eccentric support 19 of the cylinder block carrier 9 and a plane control surface 11. In distinction from the embodiments before mentioned the cylinder block 7 does not however follow the movement of the piston rods 6 by means of the pistons 8, a double cardan joint 25, 26 being provided for causing the follow-up movement by a member 28, which is non-rotatably mounted in the cylinder block by means of a piston 29. A double cardan joint is required because, as mentioned above, the cylinder block 7, during a stroke adjustment, undergoes slight displacements due to the eccentric support at 19. As in contrast to Fig. 2 the cylinder block is not supported between two spherical surfaces, it is necessary to guide the plane control surface by means of a special centering member 27.

25 The invention is not restricted to the embodiments described, there being further possibilities of construction by suitable combination of the details described above with other known features.

What is claimed is:

30 1. In a hydraulic pump of the piston type, a cylinder block formed with a plurality of cylinder bores, means for supporting said block for rotation about its axis, pistons in said bores, a driving flange mounted for rotation about its axis, mounting means for said flange, a centering ball concentrically connecting said block and said flange, the center of said ball lying on both of said axes, piston rods operatively connecting said pistons and said flange, said pistons and said bores being so related as to cause said block and said flange to rotate in synchronism, said supporting means for said block being pivotally connected with said mounting means for said flange to allow relative inclination of said axes to cause variations of the stroke of the pump in response to variations of inclination of one of said axes relative to the other axis, the axis of the pivotal connection of said supporting means and said mounting means being spaced from said center of said ball and the axis of said driving flange to produce a lever arm which is subjected to the force exerted by said pistons when there is relative inclination of the axes, to decrease the inclination and consequently the stroke of the pump, such force corresponding to the fluid pressure of the pump, and resilient means for causing relative inclination of the axes by exerting a force to increase the relative inclination of the axes and consequently the stroke of the pump.

60 2. In a hydraulic pump of the piston type as claimed in claim 1, said centering ball being connected to a piston slidably mounted in a central bore of said cylinder block and provided with spring means for urging the end face of the block against its supporting means.

70 3. In a hydraulic pump of the piston type as claimed in claim 1, said centering ball being connected to a piston slidably mounted in a centering bore of said cylinder block, and said bore communicating with the pressure side of the pump by a check valve so as to dampen the reversing motion of said cylinder block from its deflected position.

HANS MOLLY.
